UNITED STATES PATENT OFFICE.

SIDNEY R. LAMB, OF NEW YORK, N.Y.

GAME APPARATUS.

1,170,828.

Specification of Letters Patent.

Patented Feb. 8, 1916.

Application filed February 8, 1912. Serial No. 676,324.

To all whom it may concern:

Be it known that I, SIDNEY R. LAMB, a citizen of the United States, residing at New York city, county of New York, and State 5 of New York, have invented certain new and useful Improvements in Game Apparatus, fully described and represented in the following specification and accompanying drawings, forming a part of the same.

10 The object of this invention is to provide an improved game apparatus which shall afford amusement and also give opportunity for the exercise of skill in its use.

15 Features of the invention may be embodied in apparatus for use in playing various games.

An apparatus embodying all the features of the invention in a preferred form comprises a representation of a face, and especially a human face, with an open mouth and provided with teeth showing normally between the lips, and mounted so that when struck they will disappear from sight, and a ball tethered by means of a stretchable 20 elastic string for striking the teeth when released after being drawn away from the face to stretch the tether string. By holding the ball so that the string shall pull tangentially thereon and then by releasing 25 it with the fingers suitably placed on the ball, it may be directed so as to cause it to strike to one side or the other, or above or below the point of attachment of the inner 30 end of the tether string as desired, all as 35 more fully explained hereafter.

40 A full understanding of the invention can best be given by a detailed description of a construction embodying certain features of the invention in a simple form, and of a preferred construction in which the invention is embodied in an apparatus having a face with an open mouth and disappearing teeth as above referred to, and such 45 a description will now be given in connection with the accompanying drawings, in which—

50 Figure 1 is a front view in elevation of a preferred form of game apparatus in which the main body or target of the apparatus represents a human face and the disappearing indicators are formed to represent teeth showing in the open mouth of the face. Fig. 55 2 is a broken rear view. Fig. 3 is a central vertical section on line 3 of Fig. 2, and Fig. 4 is a detail referred to hereinafter.

Referring now to the drawings, the target

10^a, as shown in Fig. 1, is formed or marked to represent a human face having an open mouth 30, and having disappearing indicators made to represent upper and lower 60 teeth 31. The upright plate which is shaped and marked to represent the face is, as shown here, mounted in a solid base 32. It will be understood, of course, that a folding base might be provided in any suitable manner. The striking ball 20 is shown, as before, tethered to the face preferably at a point above the mouth by means of a stretchable, elastic string 21.

15 The teeth may be formed in any suitable way so as to disappear when struck from the front. As shown in Figs. 2 and 3, each tooth is formed by, or carried by, the end of a spring piece or carrier 33 which extends back of the plate forming the face and is 20 doubled on itself and provided with a rearwardly extending end 34. These doubled spring pieces are mounted in suitable openings 35 in the end walls or flanges of a back plate 36 which is secured on the back of the 25 face plate behind the mouth, and the rearwardly extending ends 34 project through other openings 37 in the plate 36 so as to 30 guide these tooth-carrying spring pieces. When in position with its tooth showing in 35 the mouth, each spring piece is held with its tooth in this position by a stop or detent 38 which engages the edge of the face plate and prevents its moving upward or downward as the case may be under the pressure of a 40 spring 40. When a tooth is struck from the 45 front or otherwise pushed inward, however, as indicated by dotted lines in Fig. 3, its detent 38 will be moved away from the face plate and the tooth and its spring carrier 50 will be free to move under the pressure of its spring 40 to carry the tooth out of sight 55 behind the face plate. Teeth which have been released and have disappeared may be 60 readily returned to normal or visible position by pressing upward or downward, as 65 the case may be, on the rearwardly extending ends 34 of their corresponding carriers. By drawing the ball forward to stretch the 70 string and then releasing it in such a way as 75 to direct its flight, the various teeth may, therefore, be struck and caused to disappear. By holding the ball so that the elastic string 80 shall pull tangentially thereon and then releasing while a finger is more or less in 85 front of the ball, the ball may be caused to 90 strike any desired portion of the target 95

100

105

110

either above or below or to either side of the point of attachment of the tether string to the target, and may, therefore be directed with the idea of striking any desired tooth.

5 5. A free ball might, of course, be used to throw at the teeth, especially if the face were of large size.

It may sometimes be desirable to arrange the apparatus so that one or more of the 10 teeth will be permanently set in position or prevented from disappearing. In Fig. 4 a single tooth 31^a is shown as secured permanently to the rear side of the face plate.

What is claimed is:

15 1. A game apparatus comprising a target made to represent a face with an open mouth and having teeth which normally show in the mouth, and a striking ball tethered by a stretchable elastic string, the teeth being 20 formed by a plurality of independently movable parts mounted to disappear from sight when hit by the ball.

25 2. A game apparatus comprising a target made to represent a face with an open mouth, and having teeth normally showing in the mouth, the teeth being formed each of an independently movable part mounted to disappear from sight when hit from the front.

30 3. A game apparatus comprising a target made to represent a face with an open mouth, and having teeth normally showing in the mouth, the teeth being mounted to disappear from sight when hit from the front.

35 4. A game apparatus comprising a target

made to represent a face with an open mouth, and having teeth normally showing in the mouth, and means for holding said teeth in normal position and for causing them to disappear when struck.

40

5. A game apparatus comprising a target made to represent a face with an open mouth, and having a plurality of teeth normally showing in the mouth, and means for holding each of said teeth in normal position 45 independently of the others and for causing it to disappear when struck.

45

6. A game apparatus comprising a target made to represent a face with an open mouth, and having a plurality of disappearing teeth and one or more fixed teeth, and means for holding said disappearing teeth in visible position and for causing them to disappear when struck.

50

7. A game apparatus comprising a representation of a human face with an open mouth, and having a plurality of disappearing teeth normally showing in the mouth, retracting means for each of said teeth formed to cause the tooth to disappear when 55 struck, and a striking ball tethered by a stretchable elastic string.

55

In testimony whereof, I have hereunto set my hand, in the presence of two subscribing witnesses.

SIDNEY R. LAMB.
